(57) **CLAIM**

I claim the ornamental design for a spray dispenser, as shown and described.

DESCRIPTION

FIG. 1 is a front perspective view of the spray dispenser; FIG. 2 is a front elevational view of the spray dispenser shown in closed condition hiding the spray nozzle portion; FIG. 3 is a top plan view of the spray dispenser; FIG. 4 is a bottom plan view of the spray dispenser; FIG. 5 is a side elevational view of the spray dispenser; FIG. 6 is a rear elevational view of the spray dispenser; and, FIG. 7 is a front elevational view of the spray dispenser shown in opened condition showing the spray nozzle portion.

The broken lines in the drawings are for illustrative purposes only and form no part of the claimed design.
